United States Patent Office

Des. 207,132
Patented Mar. 7, 1967

207,132

PACKAGING TRAY

Richard E. Reny, Westport, Conn., assignor to Keyes
Fibre Company, Waterville, Maine, a corporation of Maine

Filed July 22, 1966, Ser. No. 3,179

Term of patent 14 years

(Cl. D58—12.6)

Fig.1.

Fig.2.

Fig.3.

FIG. 1 is a top plan view of a packaging tray embodying my new design;

FIG. 2 is a side elevational view of the packaging tray of FIG. 1; and

FIG. 3 is an end elevational view of the packaging tray of FIG. 1.

I claim:

The ornamental design for a packaging tray, as shown.
